(57) **CLAIM**

The ornamental design for a camera for a robotic arm, as shown and described.

DESCRIPTION

FIG. 1 is a bottom, front and left side perspective view of a camera for a robotic arm showing our new design;

FIG. 2 is a top and left side perspective view thereof;

FIG. 3 is a bottom plan view thereof;

FIG. 4 is a top plan view thereof;

FIG. 5 is a right side elevation view thereof;

FIG. 6 is a left side elevation view thereof;

FIG. 7 is a front elevation view thereof; and,

FIG. 8 is a back elevation view thereof.

The broken lines depict portions of the camera for a robotic arm in which the design is embodied that form no part of the claimed design.
